UNITED STATES PATENT OFFICE.

LOUIS M. SPENCER, OF HIGHLAND PARK, MICHIGAN.

TRAILER-DUMPING MECHANISM.

1,424,426.

Specification of Letters Patent. Patented Aug. 1, 1922.

Application filed June 25, 1917, Serial No. 176,648. Renewed May 18, 1922. Serial No. 562,038.

To all whom it may concern:

Be it known that I, LOUIS M. SPENCER, a citizen of the United States, and residing at Highland Park, in the county of Wayne and 5 State of Michigan, have invented a new and Improved Trailer-Dumping Mechanism, of which the following is a specification.

It is customary to provide motor trucks with tilttable bodies and also to equip them 10 with a hydraulic (oil) hoist and a gear pump actuated by the propelling engine whereby the body may be tilted for dumping purposes. Again, it has been proposed to mount the front end of a two-wheeled 15 running gear on the rear end of a tractor, said running gear having a tilttable body and the tractor having a drum around which passes a cable for tilting the body. This construction is objectionable in that toothed 20 reversing gearing is required, which is noisy and subject to wear, and also because it necessitates the use of friction brakes, which both require constant attention during the lowering operation and which render the 25 control of the heavy body uncertain. The construction also fails to provide any automatic stop means; in other words, unless the driver manipulates the control mechanism the drum would continue to take in cable 30 until breakage resulted. In still another construction, a hydraulic hoist has been mounted on a two-wheeled running gear, the front end of which is carried by a tractor, but the mechanism whereby the hoist is actuated from the engine of the tractor is necessarily complicated and not subject to convenient control. In each of these instances 35 the load which can be carried, or the dischargeable load, is that which may be received in the single tilting body.

It has also been the practice in railway trains to tilt any one of a series of cars by means of mechanism located on a separate leading car, said mechanism being itself actuated by a locomotive. This construction is unsuitable for street use for various reasons, among which may be mentioned the fact that it could not pass around sharp corners; it also requires at least three vehicles 45 to carry one dischargeable load and is prohibitive for that cause alone.

The present invention aims to greatly increase the dischargeable load capacity of a street or roadway train (which is particularly valuable on hauls of considerable dis-

tance), and it consists in a truck having a propelling engine, a reduction mechanism and a tilting body together with a trailer having a tilttable body, and means whereby the reduction mechanism may be utilized to 60 dump either body at will, and whereby the tilting of either body is automatically stopped at a point such that breakage of the operative parts is avoided. In the embodiment shown a hydraulic (oil) hoist constitutes the reduction mechanism, but other devices of a widely different nature, such for example, as a hoisting drum or a screw hoist and proper connections, might serve the same general purpose, although the hydraulic hoist is much to be preferred. The invention also consists in a truck having a 65 tilttable body together with a trailer having a tilttable body, and means for utilizing the engine of the truck for tilting either body at 70 will, said means including a draw-bar connection from the rear end of the frame of the truck to the front end of the frame of the trailer and cable means extending across from the trailer to the truck, whereby the 75 springs of the vehicles are relieved of the pull of the cable. The invention also consists in certain improvements in the trailer, whereby a maximum length of body (tilttable about a horizontal axis near the rear 80 thereof) consistent with dumping from the power on the truck is secured; also in certain improvements whereby the hoisting mechanism on the trailer may be manufactured as a unit with substantially no change 85 in the trailer further than the provision of a few bolt holes in the frames thereof for allowing the hoisting mechanism to be bolted in place; also in certain improvements in the steering mechanism of the trailer, 90 whereby the draw-bar may be made to extend directly between the frames. The invention further consists in the details of construction shown, described and claimed.

The present construction is an improvement on that shown in my application for patent on trailer dumping mechanism, Serial Number 137,093, filed December 15, 1916.

In the drawings, Fig. 1 is a side view, 105 parts being broken away, showing a preferred embodiment of my invention. Fig. 2 is a fragmentary plan view corresponding thereto. Fig. 3 is a section on the line 3—3 of Fig. 1. Fig. 4 is a section on the line 110

4—4 of Fig. 1. Fig. 5 is a fragmentary side view of the upper end of the hoisting mechanism on the truck. Fig. 6 is a front view of the trailer. Fig. 7 is a fragmentary front view showing one manner of attaching the trailer body tilting cable to the body. Fig. 8 is a perspective view, parts being broken away, showing the draw-bar and its relation to the steering bar of the trailer. Fig. 9 is a side view showing a modification. Fig. 10 is a section on the line 10—10 of Fig. 9. Fig. 11 is a section of the trailer on the line 11—11 of Fig. 9. Fig. 12 is a section through the upper end of the piston rod shown in Fig. 9. Fig. 13 is a fragmentary plan view corresponding to Fig. 9. Fig. 14 is a diagrammatic section showing the preferred circulatory system in the hydraulic hoist shown in Figs. 1 to 8, inclusive, together with certain automatic stop means whereby the trailer may be automatically limited in its tilting movement regardless of the automatic stop means for the truck. Fig. 15 is a side view showing a second modification. Fig. 16 is a section on the line 16—16 of Fig. 15. Fig. 17 is a section on the line 17—17 of Fig. 15. Fig. 18 is a vertical longitudinal section through the hoisting trailer-carried mechanism shown in Fig. 15. Figs. 19 and 20 are sections on the lines 19—19 and 20—20 of Fig. 15. Fig. 21 is a fragmentary side view corresponding to Fig. 15 showing another way of attaching the trailer dumping cable to the piston rod. Fig. 22 is a fragmentary rear elevation corresponding thereto. The circulatory system is omitted in Figs. 1, 9 and 15 for sake of clearness.

1 and 2 indicate the front and rear wheels of a motor truck, 3 the side bars of the frame, and 4 the hopper body that includes the side bars 5 and cross beams 6 and is adapted to be tilted about pivots 7. The truck has suitable propelling mechanism, for example, an internal combustion engine 8 (a steam engine might be used instead), a transmission 9 and a propeller shaft 10. Mounted on the body just back of the seat is a hydraulic hoisting device which may include the cross bars 12, the cylinder 13 (the base 14 of which rests on the cross bars), the piston 15 and piston rod 16, the cross bar 17 and pulley blocks 18; over the latter pass cables 19 that are secured at one end to the equalizing bar 20 and have at their opposite ends shackles 21 attached to the lower ends of the corresponding body arms 22, the latter being secured to the front end of the body and depending therefrom on each side of the propeller shaft. Consequently when oil is pumped from the upper end of the cylinder through the suction pipe 25, gear pump 26 and delivery pipe 28, the piston is caused to rise and tilt the body. See also Fig. 14. The pump may be driven in different ways,

for instance, by the propeller shaft 10 and suitable clutch mechanism 31, operated, preferably, from a point within reach of the driver by connections not shown. A valve 32 (Fig. 14) when in one position may bypass the liquid back from the pipe 28 to the pipe 25 when the body is to be lowered, and is also preferably operated by connections (not shown) extending close to the driver's seat. It will be noted that when the piston 75 rises above the opening 33 into the expansion chamber 34 at the upper end of the cylinder, the liquid circulates without lifting the piston rod further,—in other words, an automatic stop is thus provided for limiting the movement of the piston rod. The mechanism thus far described is well known, except that the shackles 21 are, in this instance, of a freely detachable nature.

Connected to the rear cross bar 40 of the truck by means of a shackle bolt 41 having a bifurcated end 42 and a draw bolt 43 is a draw bar 44 that in the embodiment shown has its rear end joined to the front cross bar 46 of a trailer frame, the side bars 48 of which project forwardly somewhat therefrom. The connection may be conveniently made by a divided bracket 49 and bolt 50.

For the purpose of properly steering the trailer, the bolt 50 is located centrally above 95 the front axle 52 and in line with the steering knuckles thereof from which the steering arms 53 extend forwardly and are pivotally connected to the ends of the steering bar 54. Any preferred means may be employed for maintaining connection between the draw bar and the steering bar as the trailer frame rises and falls on the springs 55, for example, the depending bars 56 rigid with the draw bar and embracing the forwardly extending projection 57 on a member 58 secured to the steering bar. The rear edges of the bars 56 are normally spaced somewhat from the front edge of the steering bar to allow free swinging movement of the draw bar in a vertical plane. Draw bar and steering connections widely different in construction from that described may be employed; that shown is, however, readily manufactured from commercial 105 shapes. The bars 56 may be braced by bars 59 and 60 or otherwise, if desired.

The trailer is provided with a body 70 (which may be of the same general construction as the body 4—5—6) tiltable about 120 pivots 71 near the rear end of the side bars 48 and preferably having spaced body arms 72 depending from its front end on each side of the draw bar. By shortening the body slightly and placing the body arm back 125 of the cross bar 46, a single body arm may be used.

Extending across between the front ends of the side bars 48 is a frame 73 preferably carrying a base 74 socketed in its upper side 130

to receive the lower end of an upstanding guide 75, the upper end of said guide being braced from the outer portions of the front side of the frame by tension members 76.

5 It being desirable to supply considerable lubricant to the inner surface of the guide, the joint between it and the base may be sealed by packing (not shown). The guide is preferably formed of two L-shaped sections riveted together through their flanges as this does away with any necessity for countersinking rivets. The front side of the guide is cut away to receive the sheave 78 having bearings 79 secured in position by 10 bolts 80. Slidable vertically in the guide is a rather loosely fitting thrust bar 81, preferably a channel section opening forwardly to allow clearance for the heads of the bolts 80 and to admit a cable 82 that passes over 15 the sheave and is anchored to the lower end of the thrust bar by a cross pin 84. The upper end of the thrust bar has its web cut away to admit a sheave 88 on the axle 89, and passing over the last mentioned sheave 20 25 is a cable 90, the front end of which is preferably anchored to the bolts 80 by a perforated U-shaped metal clip 92 (Figs. 1 and 6). The other end of the cable extends down nearly to the draw bar and is there 30 fastened to the central portion of an equalizing bar 93, from the ends of which bolts, rods or cables 94 extend to the lower ends of the body arms 72 (Fig. 7). As shown, these elements are bolts having 35 divided upper ends receiving the equalizing bar and a pin connected thereto and having their lower ends bent and passed through holes in the outstanding flanges of the body arms, and retained by nuts 96. It will be 40 understood that the bolts are swingable both in respect to the body arms and equalizing bar. This construction is inexpensive and readily manufactured—other devices widely different might be used for the same 45 purpose. In order to retain the cable on the sheave 88 a suitable guard 98 is used.

The cable 82 passes downwardly from the sheave 78 and around a swivel block or guide 100 hooked into a hole formed in the 50 front side of the frame 73 (or in a lug on the base 74) midway between its ends. From the block 100 the cable 82 continues forwardly through a swivel block or guide 101 located near the rear of the truck (preferably hooked into a hole formed near the middle of the rear cross bar 40), thence 55 through a swivel block or guide 102 (preferably hooked centrally into the rear cross bar or bars 12) and finally upwardly to a 60 point near the top of the cylinder where it is normally suspended by having its end ring 105 carried by a hook 106 (Fig. 5). As shown, the hook is fixed to the expansion chamber 34 by means of a cap screw 108. 65 The cable is preferably made in two sections

joined by any suitable coupling 109 located just forwardly of the block 101 when the trailer body is lowered.

The upper end of the piston rod carries a member 110 (the precise shape of which may vary widely) having a horn 111 over which the ring 105 may be hooked. The shackles 21 or the connection 112 between the equalizing bar 20 and its anchor 113 (preferably the shackles as this allows the piston to be projected a maximum distance from the cylinder) are made of a readily detachable nature.

It will be seen that the body may be tilted in the usual manner without in any way affecting the trailer body. Should it be desired to tilt the trailer body independently of the truck body, it is only necessary to disconnect the cables 19 from the body arms 22 (or to disengage the connection 112, or in any other way remove these cables temporarily from the influence of the piston rod) and to then hook the ring 105 on the horn 111. Or, by having both the connections 21 and 112 in place and attaching the cable 82 to the piston rod in the manner stated, both bodies may be tilted simultaneously. In any event, the pull of the cable 82 is directly offset by the draw bar and the springs of both vehicles are relieved of all unusual shocks.

The parts on the trailer are preferably so proportioned in respect to the movement of the piston rod and piston that the latter uncovers the port 33 before the pin 84 rises 100 to the level of the middle of the sheave 78, consequently it is impossible to break the parts through inattention on the part of the driver. This automatic stop or cutout mechanism in some form is of the greatest 105 practical value.

The truck body may in some cases be omitted or be fixed to the frame 3; the resulting combination still possesses important advantages over present practice in 110 that the control of the various steps in the tilting of the trailer is both certain and safe and in that wear and noise is avoided.

Modification, Figs. 9 to 14:—In this instance the trailer tilting cable 120 is passed 115 over a sheave 121, mounted in a support 122 that fits over the upper end of the piston rod 16, and is anchored to the front cross bar 12 by means of a hook-and-eye connection 124. The cable 120 also passes through a block 102 hooked into the rear cross bar 12 as before, and through a guide 123, of any suitable construction, secured to the front end of the draw bar 44. From the latter it leads rearwardly beneath the draw bar and 125 under a guide 125 supported on the cross bar 46, then over a sheave 128 carried by an intermediate cross bar 129, then down around a sheave 130 on the lower end of a thrust frame or member (preferably formed 130

of two structural shapes 131 joined at their lower ends and diverging to points adjacent the side bars and there mounted to swing on a cross rod 133 carried by brackets 133' 5 rigid with the side bars 135 of the body 70 and is finally anchored to a cross bar 134. A coupling 109 is used as before.

Assuming that the thrust frame is about midway in the length of the trailer body, it 10 will be seen that the hoisting mechanism on the truck is given substantially the same leverage on the center of gravity of the trailer load as it has on the truck load, in other words, the center of gravity of each load 15 rises practically as fast as the piston rod. The modified construction, while probably more expensive than that previously described, has an advantage in that it allows the use of a longer trailer body. As the 20 frame 131 is of less length than the cylinder, the latter should be connected to the suction pipe 25 at a proper elevation (below the opening 33) by a pipe 136 and valve 138 (Fig. 14) and the valve should be opened 25 to insure the proper automatic stop action for the dumping of the trailer.

In order to prevent the frame 131 from striking obstructions, it is preferably provided at its lower end with a strap 140 that 30 may be received in a hook 141 on the cross rod 142 when the frame is swung up into the dashed line position indicated in Fig. 9.

Modifications, Figs. 15 to 22:—Instead of using a cross bar and two sheaves, one suspended on each side of the piston rod for the 35 purpose of elevating the body, the cheaper construction illustrated in the above figures may be employed. The piston rod (which as before is preferably hollow) is divided at 40 its upper end to receive an axle 150 upon which the sheave 151 is mounted. The cable 152 (that may be in practice either a single strand as shown or a double strand, in which latter case the sheave would be double 45 grooved) is anchored to the mid portion of the front cross bar or to the cylinder base, and passes over the sheave 151 from which it depends to a point a short distance above the side bars. It is there detachably connected, say by means of a hook 153, to a 50 clevis 154 upon which the equalizing bar 155 is pivotally suspended. Members 156 that may be similar to the bolts 94 join the ends of the bar to the lower ends of the corresponding body arms 158. Cables may be 55 used instead.

In this instance the trailer may be provided with an upstanding guide 160, similar to the guide 75. A cable 161 equipped with a 60 ring 162 at its front end normally hung over a hook 163 on the cylinder base or other convenient location, extends rearwardly through a block 102 hooked to the bar 12 as before to a swivel block 164 that corresponds

to the block 100, (a block corresponding to 65 the block 101 may also be used if desired) then upwardly over a sheave 165, then downwardly about a sheave 166 rotatably mounted on an axle 167 that extends across between the flanges 168 of the thrust bar 169 and is finally anchored at 170 to the upper 70 end of the guide opposite the sheave 165. The thrust bar is preferably H-shaped in cross section and has a portion of its web removed to provide clearance for the sheave 75 166; a portion of the web is also removed at the top to receive the sheave 172 (rotatable on the axle 173) over which passes a cable (or cables) 175. The last mentioned cable may be attached to the upper end of the 80 guide and to the lower ends of the body arms in the same manner as heretofore described with reference to the cable 90.

It will be particularly noted that in the embodiment of the invention illustrated in 85 Figs. 15 to 20, inclusive, the cable connection 161, on being hauled, travels at twice the speed and twice as far as the piston 16, and that the lift bar 169 moves with the same speed and stroke as the piston 16. 90 Therefore the stress in the cable or cables 161 is reduced (other things being equal) to one half the value of that in the cables 82; this correspondingly relieves the shearing stress in the connections between the cross-bars 12 and 73 and the side bars of the vehicle, and in the draw bar or thrust connection 44 and permits the use of smaller and more readily bendable cables. In this construction the piston 16 still exercises the 100 same leverage on the body 70 as on the body 4 (except as modified by friction).

Instead of connecting the cable 161 to the hook 153 (which is then detached from the clevis 154) in tilting the trailer body, it may 105 lead up to the top of the cylinder and be connected to a U-shaped bar 180 (the ends of which are perforated to receive the ends of the axle 150) by means of a hook 181, as indicated in Figs. 21 and 22. Suitable cable 110 guards are preferably used.

In the modification, Fig. 15 the thrust bar 169, as in the case of the bar 81, Fig. 1, is thus caused to move at the same speed as the piston rod and the latter therefore works 115 with substantially the same leverage on both truck body and trailer body. To prevent breakage, the parts are so proportioned that the piston passes the port 33 before the sheave 166 reaches the sheave 165. Should 120 it be desired to tilt both bodies at the same time, both pulling connections are made, as is obvious. In the modifications shown in Figs. 15 to 20, the U-portion of the clevis 154 may be duplicated on the under side of the bar 155, as shown at 183 (Fig. 17), and the ring 162 or the hook 181 attached there- 125 to.

While but one cable between the trucks is shown in the several embodiments, it is apparent that in the heavier vehicles at least it may be advisable to use two cables side by side (which in effect constitute a single run of cable) together with double-grooved pulleys or sheaves, thereby avoiding any difficulty which might arise from failure of a single strand to bend properly about the 10 said guiding members, and the word "cable" as used herein indicates either one or the other, or any equivalent flexible element, for example, a chain. It is evident that, although but one trailer is shown, others may 15 be added and tilted by duplicating the cables 82, 120 or 161, as the case may be, and associated mechanism.

The details of construction may obviously be changed considerably without departing 20 from the spirit of my invention. I do not, therefore, wish to be limited except as indicated by the subjoined claims.

I claim:—

1. A roadway train comprising a truck 25 having a tiltable body and a propelling engine, a trailer having a tiltable body, and means whereby the propelling engine may be utilized to tilt either body at will, said last named means including means whereby 30 the tilting of the body of the trailer is automatically limited.

2. A roadway train comprising a truck having a tiltable body and a propelling engine, a trailer having a tiltable body, and 35 means carried entirely by the vehicles whereby the propelling engine may be utilized to simultaneously tilt both bodies, said last named means including means for automatically limiting the tilting of the body of 40 the trailer, whereby breakage is avoided.

3. A two-vehicle roadway train comprising a steerable pulling vehicle having a propelling engine and a spring supported frame, a four-wheeled trailer having a 45 spring supported frame and a tiltable body thereon, a pull-and-thrust connection extending across from the rear end of the first mentioned frame to the forward portion of the trailer frame, said connection being so 50 constructed and arranged that the pulling vehicle may swing sharply in respect to the trailer, means for utilizing said engine to tilt the trailer body, said means including cable hauling means on the pulling vehicle 55 driven by the engine thereof, and a cable extending from said cable hauling means across between the frames of the vehicles through which force for tilting the body is transmitted, the construction and arrangement 60 of the parts being such that the springs are relieved from thrusts incident to the tilting operation.

4. A two-vehicle roadway train comprising a steerable pulling vehicle including a

propelling engine, a trailer attached to said 65 pulling vehicle by a draw bar connection, said connection being so constructed and arranged as to allow the vehicles to turn about sharp corners, said trailer having a spring-supported frame and a tiltable body on said 70 frame, said draw bar connection extending across from the front end of the trailer frame to the pulling vehicle, and means carried entirely by the two vehicles for utilizing the propelling engine to tilt the trailer 75 body at will, the construction and arrangement of the parts being such that the springs of the trailer are relieved of stress incident to the tilting operation.

5. A highway train comprising a truck 80 having a spring supported frame and a propelling engine, a body mounted on the frame to tilt, a trailer having a spring supported frame and a body mounted thereon to tilt, a pull-and-thrust connection extending 85 across from the rear end of the truck frame to the front end of the trailer frame, and means for utilizing the engine to tilt either body at will, said means including a flexible member extending across between the two 90 frames, the construction and arrangement of the parts being such that the springs are relieved from thrusts in the tilting operation.

6. A roadway train comprising a truck 95 having a propelling engine, a trailer having a tiltable body, a slidable member on the truck, means for utilizing the engine to actuate said slidable member, means for utilizing the slidable member to tilt the trailer 100 body, said last named means including a single run of cable anchored to the slidable member and passing across between the bodies through which all stress for tilting the body is exerted.

7. A roadway train comprising a truck having a propelling engine and a body tilt- 105 able thereon about a horizontal axis near the rear end thereof, an upright hoisting device forward of the front end of the body, said 110 hoisting device including a projectable member, a trailer having a tiltable body, means for utilizing said projectable member for tilting either of the bodies at will, said last named means including a single run of cable 115 detachably anchored to the upper end portion of the projectable member and passing across between the bodies through which all stress for tilting the trailer body is transmitted.

8. A roadway train comprising a truck having side bars and a propelling engine, an upright hoisting mechanism mounted on the side bars, said mechanism including a projectable member, a trailer connected to 120 the rear end of the truck by a draw bar connection, a tiltable body on the trailer, means for utilizing the projectable member for

tilting the body, said means comprising a cable guide secured to the hoisting mechanism near the base thereof and a cable co-operative with the projectable member and 5 passing about said cable guide.

9. A roadway train comprising a truck having a frame and a propelling engine, said frame including a rear cross bar, hoisting mechanism mounted on the frame, said 10 mechanism including a projectable member, a trailer connected to the rear end of the truck by a draw bar connection, a tiltable body on the trailer, means for utilizing the projectable member for tilting the body, said 15 means comprising a cable guide secured to the rear cross bar and a cable co-operative with the projectable member and passing about said cable guide.

10. Load carrying means comprising a 20 steerable vehicle having an upright guide and a slidable member movable up and down in said guide, a cable detachably fixed to the slidable member and itself being positioned substantially in the central longitudinal 25 plane of the vehicle, a wheeled frame drawn by said vehicle, a tiltable body on said frame, and means whereby said cable is connected to said body to tilt the latter.

11. A roadway train comprising a pulling 30 vehicle having an upright cylinder, a piston rod slidable therein, a trailer comprising a tiltable body, a rigid member surrounding the upper end portion of the piston rod, a cable for tilting the trailer body, 35 said cable being detachably fixed to the rigid member substantially in the central longitudinal plane of the vehicle.

12. A roadway train comprising a steerable 40 vehicle having an upright guide and a thrust bar slidable in said guide, a cable detachably fixed to the upper end of said thrust bar and leading downwardly therefrom substantially in the central longitudinal 45 plane of the vehicle, a wheeled frame drawn by said vehicle, a vehicle body tilt- 50 able on said frame about a transverse axis near its rear end, and means associated with the cable whereby the forward end of the body is elevated at substantially twice the 55 speed the thrust bar slides in the guide.

13. A roadway train comprising a steerable 55 vehicle having a propelling engine, a trailer having a frame and a body tilttable thereon, cable hauling means on the truck 60 driven by the engine thereof, a cable hauled by said means, and means interposed between the trailer frame and body actuated by said cable for tilting said body, said cable hauling means including means whereby the tilting of said body is automatically limited.

14. A vehicle comprising side bars and 65 a body tilttable about a horizontal axis near its rear end, a cross-bar construction rigid with the side bars, a base resting on the

cross-bar construction and rigid therewith, an upright guide mounted on said base and rigid therewith, a thrust bar slidable up and down in said guide, means associated with the upper end of the thrust bar for 70 tilting the body when said thrust bar is elevated, a sheave mounted on the upper end of the guide, said base and said cross-bar construction forming a guide support, a rotatable member on the guide support, and 75 a cable passing about said rotatable member and said sheave and anchored to the lower end of the thrust bar for lifting said thrust bar.

15. A vehicle comprising side bars and a 80 body tilttable about a horizontal axis near its rear end, an upstanding guide forward of the body, a thrust member slidable therein, a pair of spaced body arms secured to the front end of the vehicle, a cable passing centrally over said thrust member, the forward end of the cable being anchored, the rearward end of the cable depending to a point near the body arms, and means for distributing the pull from said cable substantially equally to the body arms. 90

16. A two vehicle roadway train comprising a steerable tractor having a propelling engine, a four-wheeled trailer having a 95 spring supported frame and a tiltable body thereon, a pulling connection extending directly from the tractor to the forward portion of the trailer frame, and means for utilizing said engine for tilting the body while the trailer is connected to the frame, 100 whereby the trailer springs are relieved of thrust otherwise incident to the tilting operation.

17. Load carrying means comprising a steerable vehicle having a propelling engine, a wheeled frame swingable in respect thereto, a body tilttable on said frame to dump, means interposed between said wheeled frame and said body for tilting the latter, and means carried on said vehicle for actuating said interposed means and for automatically limiting the tilting of said body. 105

18. In combination, a first pulling wheeled frame having a propelling engine, a second 115 wheeled frame drawn by said first frame and having a tiltable body, means on the second frame operated by said engine for exerting a lifting force between said second frame and said body to tilt the latter, and means on the first frame for automatically limiting the tilting of the body. 120

19. Load-carrying mechanism including a frame, a body tilttable thereon, a first reciprocable member, a second reciprocable member, a cable connection through which force is transmitted from said first member to said second member, a cable connection through which said second reciprocable member operates to tilt the body, and auto- 125 130

matic stop means operative on the first reciprocal member to limit the tilting of said body.

20. Load carrying mechanism including a first wheeled frame, a body tilttable thereon, a second wheeled frame, cable hauling mechanism on the second frame, a cable hauled by said mechanism, means on said

first frame operated by said cable and exerting a lifting force between said first frame and said body to tilt the body, said cable hauling means including an automatic stop device for limiting the tilting of said body.

LOUIS M. SPENCER.
